UNITED STATES PATENT OFFICE.

JAMES MURCHIE, OF LONDON, ENGLAND.

CARBURETER.

1,246,982.

Specification of Letters Patent. Patented Nov. 20, 1917.

Application filed April 10, 1913. Serial No. 760,216.

To all whom it may concern:

Be it known that I, JAMES MURCHIE, of London, England, have invented certain new and useful Improvements in Carbureters for Internal-Combustion Engines, of which the following is a specification.

This invention relates to an improved carbureter for internal combustion engines and has for its object to provide a carbureter for use in connection with internal combustion engines by means of which an explosive mixture for use in such engines can be readily obtained from either light or heavy hydro carbon oils or from a combination of oils of different specific gravity such as petrol and petroleum for instance.

The invention broadly consists of a carbureter provided with two float chambers—one for light and the other for heavy oil and means for controlling the supply from these chambers such as will enable either of the two oils to be employed separately or both together, in suitable proportions. Further features of importance comprise means by which a suitable temperature is produced and maintained in the heavy oil vaporizer under all conditions of load and the general construction and arrangement of parts designed for efficiency and convenience in use and to provide the maximum of flexibility.

In the accompanying drawings I have illustrated an example of a carbureter constructed in accordance with my invention.

Figure 1 being an elevational view partly in section of the carbureter as a whole.

Fig. 2 is a plan view thereof.

Fig. 3 is a vertical section of the heavy oil vaporizing chamber on line A. B of Fig. 1.

Fig. 4 is a sectional view through the three way valve used in combination with my invention.

Referring to these drawings the numeral 1 designates the exit passage from the carbureter to the engine which is provided with the usual throttle valve 2 and leads from a three-way cock 3, the position of the plug 4 of which determines whether the light oil carbureter or the heavy oil vaporizer or both are in use.

The hollow plug 4 of this cock 3 is in communication with an extra air valve 5, which consists of a spring controlled piston 6 moving in a cylinder 7 provided with air ports 8 which are normally closed and gradually open as the suction of the engine increases in

intensity. The position of the cylinder 7 and the relative opening of the air port or ports 8 is determined by the position of a lever 9, so that the mixture can be controlled directly by the driver. In the arrangement shown the lever 9 rotates a casing 10 and with it the sleeve 11 provided with a pin 12 which co-operates in an oblique slot 13 in a sleeve 14 concentric with the sleeve 11. By this means the relative positions of the ports 8 and the piston 6 can be adjusted. The extra air valve is always in communication with the inlet to the engine.

In one position of the three-way cock 3 the petrol or light oil carbureter 15 only is in use. This consists of an induction tube 16 provided with a central jet 17 communicating with a float chamber 18 or other constant level device. The base of the induction tube 16 is provided with a chamber 19 having perforations 20 through which the air passes. This chamber acts as a vaporizer and is supplied with warm air from a jacket 51 communicating by means of a pipe with a source of warm air such as another chamber 47 surrounding a hot part of the heavy oil vaporizer. It will be seen that the pipe 52 is connected to the jacket 51 and chamber 47 respectively through the medium of the nuts 53 and 49 thereby insuring a rigid connection 85 therebetween. The chamber 47 is of course, heated by means of the warm air passing from the heating tube, with the result that air drawn into pipe 52 through channel 48, and chamber 47, is heated.

In a second position of the three-way cock 3 the petroleum carbureter only is in use. The petroleum is supplied by means of a float chamber 21 to a jet 22 in an induction tube 23 which is inclined downward and discharges into the upper part of a heated vaporizing chamber 24. A spring controlled valve 25 is provided at the highest point in the induction tube 23 and the jet 22 from which the oil is drawn is adjustable by means of a needle valve 26. The mixed air and petroleum are drawn into the aforesaid chamber 24 which surrounds the upper part of the vaporizer tube 27 through which the exhaust gases of the engine pass. This chamber 24 is provided with additional air valves 28. A number of holes 29 are made in the base of this chamber and through these holes the mixture passes into an annular chamber 30 surrounding the vaporizer 100 105 110

2

tube 27. The surface of this annular chamber is provided with ribs or projections 31 of suitable shape to give a large heating surface and to induce a thorough mixing of the vapor and air. A sleeve or curtain 32 of metal is provided in the annular chamber 30, so that the mixture after passing over the hot inner surface, rises outside the sleeve 32 (leaving any unvaporized oil behind) and 10 enters the three-way cock 3 by means of an opening 33 in the side of the annular chamber. A cock 34 is provided on the side of the annular chamber 30 for the removal of any unvaporized oil.

15 The heating tube 27 through which the exhaust gases pass is for the most part vertical, and is provided with two openings at the top and three at its base. One of the openings 35 at the top is for connection with the exhaust of the engine, and the other 36 is provided with a cap 37, which is removed when the blow lamp is used for initial heating and provides an exit for its products of combustion. Of the three openings at the 20 base 38, one is connected to the silencer of the engine, the second 39 is the opening into which the flame of the blow lamp is directed when it is desired to start up on the heavy oil. The third opening 40 is only of use 25 when heated air is supplied to the petrol vaporizer the heating device being in this case connected to the said opening. Internal ribs or projections 41 are provided on the inside of this vaporizer tube 27 to give 30 greater heating surface and increase the coefficient of heat transmission. In the center of this tube a hollow metal conical valve 42, is supported in a vertical position and controlled by a spring 43 and dash pot 44 moves 35 the valve 42 upwardly with the result that the enlarged portion thereof engages the inclined walls of the tube 27 which forms the seat for the valve 42 and closes the vaporizer when the engine stops. It will, of course, 40 be seen that the valve opens again by the pressure of the exhaust gases thus adjusting the size of the opening through the heating tube to the volume of the exhaust gases and maintaining and conserving the heat of 45 the vaporizer. It is well known that the co-efficient of heat transmission is a function of the velocity of the heating fluid and increases as this velocity increases, and, since also, this arrangement scrubs the metal 50 surfaces, the efficiency of the apparatus is 55 very high. The hollow conical valve 42 is filled with aluminum filings whose high specific heat and low conductivity still further helps to maintain the temperature of 60 the vaporizer.

The needle valve 26 of the jet 22 and the air valve 28 are adjusted when running on petroleum, so that under all conditions of

loading the extra air valve as formerly adjusted gives a correct mixture at all speeds. 65

Under these circumstances the three-way cock 3 may be placed in such a position as to put the engine into communication with both the petrol carburetor and the heavy oil vaporizer at the same time. 70

The use of the light oil enables the engine to start from cold and to change over to heavy oil after the vaporizer for heavy oil has become hot.

In the absence of light oil however the heavy oil vaporizer may be initially heated with a blow lamp through the opening provided as aforesaid before starting the engine. 75

What I claim and desire to secure by Letters Patent is:

1. In a carburetor, a casing having an intake port, a vaporizing chamber formed by the casing, a heating tube extending into the vaporizing chamber and being spaced therefrom to provide a fuel passageway, said vaporizing chamber having openings adjacent the upper extremities thereof to allow fuel to pass to the fuel passageway, means supported within the fuel passageway for dividing the same into an outer and inner compartment, said means terminating short of the length of the heating tube, ribs on the heating tube for providing fuel passageways, and said casing having an opening to allow heated fuel to pass therethrough. 80

2. In a carburetor, a casing having an intake port, a vaporizing chamber formed by the casing, a heating tube extending into the vaporizing chamber, said heating tube being spaced from the walls of the casing to form a fuel passageway, said vaporizing chamber having openings to allow fuel to pass to the fuel passageway, a sleeve supported in the fuel passageway for dividing the same into an outer and inner compartment, and said casing having an opening to permit vaporized fuel to pass therefrom. 85

3. In a carburetor, a casing having an intake port, a vaporizing chamber in the casing, a heating tube spaced from the walls of the casing to form a fuel passage-way, substantially vertical ribs provided on the heating tube, means extending into the fuel passage-way and co-operating with the ribs for forming independent fuel passage-ways, and said vaporizing chamber having openings to permit fuel to flow therefrom to the independent fuel passage-ways. 90

In testimony whereof I affix my signature in presence of two witnesses.

JAMES MURCHIE.
